UNITED STATES PATENT OFFICE.

JOHN D. NEWSOM, OF DETROIT, MICHIGAN.

CARBURETER.

Specification of Letters Patent. Patented Nov. 19, 1918.

1,285,329.

Application filed November 8, 1916. Serial No. 130,293.

To all whom it may concern:

Be it known that I, JOHN D. NEWSOM, a citizen of the United States of America, residing at Detroit, in the county of Wayne 5 and State of Michigan, have invented certain new and useful Improvements in Carbureters, of which the following is a specification, reference being had therein to the accompanying drawings.

10 This invention relates to carbureters and the object of my invention is to provide a novel outlet member adapted to impart a whirling movement to a volatile liquid entering the member, and in combination with 15 a mixing chamber produce films of volatile liquid at walls of the mixing chamber to be disintegrated by a forcible supply of air or fluid entering the mixing chamber through the perforated walls thereof. This object 20 is attained by a three part outlet member including a spray nozzle, a main air valve, and a mixing or disintegrating chamber. The air valve may be suspended or adjusted 25 relative to the nozzle to regulate portions of fuel and air, giving proportionately less fuel to air when fixedly held, by constriction at the spray nozzle, and more fuel to air when adjusted to relieve the constriction of the spray nozzle.

30 A further object of my invention is to provide an outlet member that may be embodied in any carbureting or atomizing device having suitable supplies of fluids and liquids with means of controlling the same.

35 A still further object of my invention is to provide a mixing device for various industrial purposes, wherein the parts are constructed with a view of reducing the cost of manufacture and at the same time retain 40 those features by which safety, durability and ease of assembling are secured. With these ends in view, my invention resides in the novel construction, combination and arrangement of parts to be hereinafter specifically described and then claimed.

45 Reference will now be had to the drawing, wherein—

Figure 1 is a vertical sectional view of a carbureting device in accordance with my 50 invention, and Fig. 2 is an enlarged plan of a spray nozzle.

In the drawing, 1 denotes a tubular body, and the upper end of said body is provided with a head 2 having an inner annular seat 55 3 and an outer annular seat 4. Concentric of the head 2 is a main well 5 communicating

with a valve-way 6 and an air intake passage 6^a in the body. The air passage is intersected by a spider 7 and an upright 8 centrally of the spider and in the longitudinal axis of the body. 60

The upright 8 has a longitudinal bore 9 with the upper end thereof communicating with lateral ports 10 in the spider 7, while the lower end of the bore receives an adjustable needle valve 11. 65

The lateral ports 10 of the body and spider are in communication with a suitable supply of volatile liquid, as gasoline, and a float chamber 12 has been shown as inclosing or surrounding the body 1. This float chamber is held on the lower end of the body 1, against a peripheral flange 13 thereof, by a nut 14 or other fastening means. Communicating with the float 70 chamber 12 is a supply chamber 15 which has the bottom thereof provided with an inlet port 16 and suitable connections 17 to a source of supply. The admission of liquid to the supply chamber 15 is controlled by a float valve 18 actuated by the short arm 19 of a float lever 20 fulcrumed in the supply chamber 15. The float lever 20 is connected to a conventional form of float 21 within the float chamber 12, and the elements 12 to 21 inclusive are of a conventional form constituting means for supplying a volatile liquid to the ports 10 of the body. 75

80 Fixed on the upper end of the upright 9 90 within the valve way 6 is a spray nozzle 22 constituting an element of an outlet member, and said nozzle has a concentric opening 23 into which the needle valve 11 extends and may be adjusted therein to regulate the area 95 of the orifice. The top of the spray nozzle 22 is convex or conical and is provided with a plurality of tangentially disposed grooves 24 through which air or other fluid may pass to commingle with the liquid drawn out of the opening 23, and these tangentially or angularly disposed grooves 24 are adapted to impart a whirling movement to the fluid and the liquid with which the fluid commingles. 100

105 Mounted upon the outer annular seat 4 of the head 2 is a cap 25 having the side walls thereof provided with a series of air intake openings. The top of the cap 25 has a concentric opening 27 and communicating therewith is an outlet connection 28, which together with the cap 25 is held in position 11

and connected to the head 2 of the body 1 by screw bolts 29 or other fastening means. The connection 28, as in the case of a manifold connection, contains the usual throttle 5 or butterfly valve 30.

Extending upwardly into the cap 25 is an annular wall 31 forming part of the head 2 and said wall has air intake openings 32 adapted for admitting air into the 10 well 5 and the chamber formed by the wall 31. Slidable between the wall 31 and the annular wall of the cap 25 is an annular shutter or auxiliary air valve 33 normally engaging the inner annular seat 3 of the head 2. The annular shutter 33 is inverted channel shaped in cross section and is weighted or balanced, as at 34, to normally close the air intake openings 32 of the wall 31. The annular shutter may be raised by 15 a reduction of atmospheric pressure in the upper part of the cap 25, particularly between the wall 31 and the annular wall of said cap, and impetus may be imparted thereto by a member to be hereinafter referred to.

Slidable in the valve-way 6 is an inverted cup-shaped regulating member 35 constituting another element of an outlet member, and said regulating member has the 20 side walls thereof provided with openings 36. The top of the regulating member 35 has a concentric outlet sleeve 37 directly above the spray nozzle 22 and the inner walls of this outlet sleeve are helically 25 grooved to coöperate with the tangentially disposed grooves 24 of the spray nozzle 22 in imparting a whirling movement to air and liquid when emitted by the sleeve 37. The upper end of the regulating member 35 30 normally rests on the spray nozzle 22 and coöperates with said nozzle in providing a restriction which may be increased in area by raising said member. The regulating member 35 is light in weight so that it may 35 be automatically elevated at the initial reduction of atmospheric pressure or suction in the well 5, and holding said member normally seated in the valve-way 6 is a resilient arm 38 extending through one or more of 40 the openings 32 of the wall 31 and connected to the annular shutter or auxiliary valve 33. The arm 38 also permits of the regulator member 35 assisting in the elevation of the shutter or valve 33.

55 Centrally of the cap 35 is an inverted frusto-conical shaped perforated shell of foraminous member 39 constituting another member of the outlet member and in proximity to the top of the regulating member 35, but providing sufficient clearance so that said member may be elevated to place the openings 36 thereof in communication with the well 5. The upper large end of the foraminous member 39 corresponds in diameter to the connection 28 and is sup-

ported on the cap 25 at the edges of the opening 27. The perforations or apertures of the member 39 may gradually decrease in diameter from the small end of the member to the large end thereof.

Extending into the foraminous member 39 is an adjustable rod 40 held by the top of the connection 28 or supported by any suitable means above the cap 25 or in the member 39. The inner end of the rod 40 has 7 a plummet shaped deflector 41 contiguous to the outlet sleeve 37 and said plummet deflector has the walls thereof in spaced relation to the walls of the foraminous member 39. The rod 40, adjacent the deflector 41, 80 has a screwthreaded portion 42 in engagement with a hanger 43 so that rotation of the rod 40 will raise and lower said hanger 43. The hanger 43 extends through one of the perforations or openings of the foraminous member 39, and under normal conditions, has the lower end thereof loosely connected to the regulator member 35. The lower end of the hanger, however, has nuts 44 or other fastening means so that the regulator member 35 may be fixed relative to the lower end of the hanger. 85 90

In operation, an initial reduction of atmospheric pressure in the well 5 pulls air and gasoline into the outlet sleeve 37 of the regulator member 35 and the grooves in the wall of the spray nozzle 22 and the sleeve 37 impart a whirling movement to the mixture. The mixture is directed toward the inner walls of the foraminous member 39 to 100 be broken up by air passing through the perforations or apertures of said member. The deflector 41 positively divides the discharge from the sleeve 37 and said deflector may be adjusted to increase and decrease 105 the restriction at the lower end of the foraminous member. Furthermore, the first suction impulse in the well 5 tends to raise the regulator member 35 which will increase the space for the outlet of air between 110 the nozzle and the regulator member. As the regulator member is raised the openings 36 thereof are gradually brought into communication with the well 5, admitting air thereto so that the air may enter the 115 lowermost perforations or apertures of the foraminous member and commingle with the mixture passing through said member.

On account of the resilient arm 38 resting on the regulator member 35 a movement of 120 the member 35 will impart sufficient impetus to the auxiliary valve 33, to coöperate with the suction in the cap 25 in raising the auxiliary air valve, thus allowing air to enter the cap and break up the mixture 125 within the foraminous member at all sides thereof.

When it is desired to obtain a very lean mixture, the regulator member 35 may be fixed relative to the hanger 43, so that by 130

rotating the rod 40 the regulator member may be raised to a desired height to permit of a desired quantity of air passing through the openings 36 and between the nozzle 22 and the regulator member 35. By the outlet sleeve 37 moving to and from the deflector 41 a restriction may be accomplished within the foraminous member, besides the restriction with which the spray nozzle 22

10 forms a part.

Irrespective of how fuel or air are admitted to the nozzle 22, members 35 and 39, these elements constitute an outlet member that is applicable to various types of mixing devices, and while it is thought that the operation and utility of the method of automatically regulating the mixture of air and gasoline by the device will be apparent to those skilled in producing explosive mixtures, it is to be understood that the structural elements disclosed in the drawing are susceptible to such changes in size, shape and manner of assemblage as fall within the scope of the appended claims.

25 What I claim is:—

1. An outlet member for a mixing device, comprising a spraying nozzle having a fuel inlet at the lower end thereof and the upper end thereof provided with tangentially disposed grooves, an inverted conical shaped foraminous member above said spray nozzle and supported independent thereof, a regulator member on said spray nozzle having an interiorly grooved outlet sleeve extending into said foraminous member adapted to coöperate with said spray nozzle in imparting a whirling movement to a mixture

injected into said foraminous member, a deflector in said foraminous member, and a connection between said deflector and said 40 regulator member and extending through said foraminous member so that said regulator member may be moved by said deflector.

2. A mixing device comprising a body 45 provided with an air well and a valve-way, a nozzle in the air well of said body adapted for communication with a suitable supply of liquid, a regulator member slideable against the walls of said valve-way and 50 controlling the initial admixture of air and liquid at said nozzle, a cap on said body provided with air intake openings, an automatically actuated auxiliary air valve slideable between said air well and the walls 55 of said cap and controlling the admission of air to said cap, an inverted conical shaped foraminous member in said cap adapted to receive the mixture from said regulator member, an adjustable deflector in said foraminous member adapted to direct the mixture against the inner walls of said member to be broken up by air entering said cap, and a connection between said deflector and said regulator member and extending 60 through said foraminous member so that said regulator member may be adjusted in the well of said body by said deflector.

In testimony whereof I affix my signature in the presence of two witnesses.
